UNITED STATES PATENT OFFICE.

FRANCIS H. RICHARDS, OF NEW BRITAIN, ASSIGNOR OF ONE-HALF HIS
RIGHT TO HOBART E. SMITH, OF NEW HAVEN, CONNECTICUT.

IMPROVEMENT IN DROP-HAMMERS.

Specification forming part of Letters Patent No. 177,960, dated May 30, 1876; application filed
November 15, 1875.

To all whom it may concern:

Be it known that I, FRANCIS H. RICHARDS, of New Britain, in the county of Hartford and State of Connecticut, have invented certain new and useful Improvements in Friction-Roll Drop-Hammers, which improvements are fully set forth in the following specification, reference being had to the accompanying drawing, showing my newly-invented drop-hammer in perspective.

In the construction of my improved drop-hammer I employ, in common with others, two friction-rolls, R R', driven by pulleys P, one of which is removed from the drawing the better to exhibit the parts supported in bearings b and b' upon a frame, F, resting upon the top of guides G G', secured to anvil A, and between which guides the hammer slides freely. These parts, with their arrangement and operation, being extensively used and well known, I omit further description of them.

The object of the present invention is to provide such means of operating the hammer H as shall place it completely under control of the operator, whereby it may be used with that variation of the weight and rapidity of the blows with which a blacksmith is accustomed to use his hammer upon the anvil—a result highly appreciated by all practical forgers.

This object I accomplish by giving to the board T, heretofore made straight throughout its length, the form of a wedge, widest at the upper end, as shown in the drawing. To render this tapered board efficient to give control of the hammer, as named, the friction-roll R is supported upon a carriage, C, operated from the hand-lever L by means of a rod, r, terminating in a wedge, W, at its upper end.

The construction and arrangement of the parts, as thus described, being understood, it is obvious that if the rolls R R' be made to revolve in such manner as to easily lift the hammer, and that if by the means described, or the equivalent, the roll R is moved to press against the board, the hammer will be lifted; but the said board being tapered, there is,

during its upward movement, continually a thinner portion of said board presented to the action of the rolls, requiring for the continuance of such upward movement of the hammer-like and proportionate continuance of the motion of roll R toward roll R', and, agreeably to the nature of the machine, a like downward movement of lever L by the hand of the operator; and as any certain downward motion of the lever L gives a corresponding upward movement to the hammer, it is obvious the reverse motion of the lever will give a downward movement thereto, and that the velocity of such movement will be exactly proportionate to the motion of the lever L, which, being in the hand of the operator, gives him complete control of the hammer H, whereby the object before named is accomplished.

I do not limit myself to the use of the wedge W to communicate motion from the lever L to the carriage C, as it is obviously merely a matter of discretion whether one or another mechanical device shall be used therefor.

In the drawing I have shown no device for keeping the carriage C against the wedge W when said wedge is raised, as, by belting the pulley P to a shaft at the left hand thereof, this is accomplished without any special device therefor; and by this means, also, the rolls are held so far apart when the hammer is not in use as to prevent them from wearing the board out of shape.

To better adapt the drop-hammer to forge articles requiring for their formation various-shaped dies or tools, D, the said die, may be arranged about and upon revolving die-beds B, which are shown retained in position by pins i.

I claim—

1. The combination, with the hammer H and friction-rolls R R', of the tapered board T.
2. The combination, with the tapered board T and friction-roll R, supported in carriage C, of the wedge W, or equivalent, and lever L.

FRANCIS H. RICHARDS.
